UNITED STATES PATENT OFFICE

WILLIAM D. WILLIAMS, JUNIOR, OF RICHMOND, INDIANA

DESIGN FOR A KITCHEN CABINET

Application filed December 9, 1932. Serial No. 46,403. Term of patent 7 years.

To all whom it may concern:

Be it known that I, WILLIAM D. WILLIAMS, JUNIOR, a citizen of the United States, residing in the city of Richmond, in the county of Wayne and State of Indiana, have invented a new, original, and ornamental Design for Kitchen Cabinets, of which the following is a specification, reference being had to the accompanying drawing, forming a part thereof.

The illustration is a perspective view of a kitchen cabinet, showing my new design.

I claim:

The ornamental design for a kitchen cabinet, substantially as shown.

WILLIAM D. WILLIAMS, JUNIOR.
